DESIGN FOR A CAN OR SIMILAR ARTICLE

Ian Benton, El Paso, Tex.

Application October 22, 1943, Serial No. 111,450

Term of patent 14 years

(Cl. D58—17)

To all whom it may concern:

Be it known that I, Ian Benton, a subject of the King of Great Britain, residing at El Paso, in the county of El Paso and State of Texas, have invented a new, original, and ornamental Design for a Can or Similar Article, of which the following is a specification, reference being had to the accompanying drawing forming a part thereof.

In the drawing:

I claim:

The ornamental design for a can or similar article, substantially as shown.

IAN BENTON.
